(57) **CLAIM**

The ornamental design for a wrist watch, as shown and described.

DESCRIPTION

FIG. 1 is a front perspective of the wrist watch embodying our design;

FIG. 2 is a top plan view of FIG. 1;

FIG. 3 is a side elevational view of FIG. 1;

FIG. 4 is a side elevational view of FIG. 1 showing the opposite side of FIG. 3;

FIG. 5 is a side elevational view of FIG. 1 showing the stem;

FIG. 6 is a side elevational view of FIG. 1 showing the opposite side of FIG. 5; and,

FIG. 7 is a bottom plan view of the wrist watch.

The broken lines in the drawings are used to show portions of the wrist watch that do not form part of the claimed design.
